UNITED STATES PATENT OFFICE.

ULDRIC THOMPSON, JR., OF HARTFORD, CONNECTICUT.

COLLAPSIBLE TUBE.

1,188,115

Specification of Letters Patent. Patented June 20, 1916.

Application filed April 1, 1915. Serial No. 18,597.

To all whom it may concern:

Be it known that I, ULDRIC THOMPSON, Jr., a citizen of the United States, and resident of Hartford, in the county of Hartford and State of Connecticut, have invented new and useful Improvements in Collapsible Tubes, of which the following is a specification.

This invention relates to collapsible tubes such as are commonly used as containers for tooth pastes, adhesives, greases and the like. Although other materials have heretofore been suggested, the tubes of this general type in common use are almost universally made of tin or of alloys or composition material which have been found to be adapted to preserve the contents and at the same time withstand the chemical action of certain ingredient or ingredients of the contents. These tubes have for many reasons proved unsatisfactory in service both to manufacturers and users, two of the principal objections being that they are expensive and when rolled or folded up in service as the contents are used, tend to break open.

It is the principal object of this invention to provide a collapsible tube of this general type wherein the body portion is made of a comparatively inexpensive material, such for example as paper or cloth properly treated and prepared, if necessary, to preserve the contents and resist injurious chemical action. This and other objects of my invention are hereinafter more particularly referred to.

Referring to the drawings which illustrate certain embodiments of my invention,—Fig. 1 is a side elevation of my improved tube; Fig. 2 is an enlarged sectional view on the line 2—2, Fig. 1, partly broken away; Fig. 3 is a detail view of the body portion of the tube; Fig. 4 is a section on the line 4—4, Fig. 3; Fig. 5 is a front elevation of a stiffener; Fig. 6 is an edge view thereof; Fig. 7 is a side view of the top of the tube; Fig. 8 is a plan view thereof; Fig. 9 is a side view of a clamping ring; Fig. 10 is a bottom plan view thereof; Figs. 11, 12 and 13 are diagrammatic representations of different methods of securing the top and body portion of the tube.

A is the body portion of the compressible tube made of a non-metallic material, preferably cloth paraffined or otherwise treated, if necessary, so as to be substantially air tight and to resist any injurious chemical

action of the particular contents for which the tube is intended. The said body is provided with a vertically extended pocket A' having a slit or opening a on the outside of said body near the bottom thereof, and a similar slit or opening a' on the inside of said body near its top. Within said pocket is a stiffening strip B of ductile metal adapted to resist distortion of the tube when full and to retain the folds as they are made from time to time as the contents are used. One end of said strip extends upward through said slit a' and is turned over to form a hook B', and its other end extending downward through said slit a is provided with a head or fastening clip B² preferably formed integral therewith, as shown, and adapted to secure the folded bottom edges of the body as clearly shown in Fig. 2. The top of the tube is made of any suitable material, preferably metal, and consists in its preferred form of a shell C having an integral annular flange C' provided with a slot c. The said top is further provided with an outlet slot C² adapted to be closed by a cap or plate D pivotally secured on said top and having an inset or projection d adapted to cooperate with said delivery opening C² removably to hold said cap in closed position. While I prefer the cap shown, it will be understood that if desired the ordinary screw cap may be employed. In securing said body portion A and said top C, the upper edge of the body portion is turned over the flange C' and the hook B' of the stiffening strip B secured in the slot c. A holder or ring E, U-shaped in cross section, is then placed over the flange C' and the edge of the body which extends over said flange, so that when said ring E is in position, as shown in Fig. 2, its inner rim e grips the turned over edge of the body which passes under it and holds it in engagement with said flange. The said ring E is secured in position by a fastening ring S of solder or the like which is run into the space between said ring E and said shell C. Preferably, as shown, the said shell is provided with indentations I, into which the solder may run and so be firmly held.

Figs. 11, 12 and 13 show diagrammatically alternative methods of securing the top and body portion. In Fig. 11 the edge of the body A is merely turned over the flange C' which is thereupon crimped to secure the top and body. In Fig. 12 the top and body are

secured as in Fig. 11 and a ring F is added for further security and to give the tube as a whole a finished appearance. In Fig. 13 a ring R of wire or the like is placed inside the flange C' and the edge of the body passed thereunder. The flange is then crimped to secure the body and top.

A collapsible tube constructed in accordance with my invention as above described, 10 can be readily and economically manufactured, and is strong and durable. The cloth of which the body portion is preferably made when coated if necessary with paraffin or the like, is well adapted to preserve the 15 substances usually offered for sale in tubes of this type and to resist damage from the chemical ingredients employed. Furthermore, my improved tube is readily compressible and has no tendency to break open 20 when folded or rolled up as the contents are used, according to the common practice.

I claim:

1. A tube for plastic material comprising a top having an outlet, a cap for said 25 outlet and a non-metallic foldable body portion provided with a longitudinally extending, foldable stiffener adapted to resist distortions of the tube when full and to retain the folds of said body portion as the 30 tube is emptied.

2. A tube for plastic materials comprising a top having an outlet, a cap for said outlet, a foldable non-metallic body portion provided with a longitudinally extending, 35 foldable stiffener, and a fastener at the end of said stiffener to secure an end of said body.

3. A tube for plastic materials comprising a top having an outlet, a cap for said 40 outlet, a flange on said top, a non-metallic body portion having its upper end extending over said flange, a holder extending on both sides of said flange adapted to hold said

body in engagement with said flange, and means to secure said holder and said top. 45

4. A tube for plastic materials comprising a top having an outlet, a cap for said outlet, a flange on said top, a non-metallic body portion having its upper end extending over said flange, a ring extending on both sides 50 of said flange adapted to grip and hold said body in engagement with said flange, and means to secure said ring and said top.

5. A tube for plastic materials comprising a top having an outlet, a cap for said outlet, 55 a flange on said top, a non-metallic body portion having a longitudinally extending, foldable stiffener engaging said flange, and means to secure said body and said top.

6. A tube for plastic materials comprising a top having an outlet, a cap for said outlet, a flange on said top, a non-metallic body portion having its upper end extending over said flange and provided with a longitudinally extending, foldable stiffener 65 engaging said flange, a ring adapted to hold said body in engagement with said flange, and means to secure said ring and said top.

7. A tube for plastic materials comprising a top having an outlet, a cap for said outlet, 70 a flange on said top, a non-metallic body portion having its upper end extending over said flange and provided with a longitudinally extending, foldable stiffener engaging said flange, a ring adapted to hold said body 75 in engagement with said flange, means to secure said ring and said top, and a fastener secured to said stiffener and adapted to secure an end of said body.

Signed by me at Hartford, Connecticut, 80 this twenty-seventh day of March 1915.

ULDRIC THOMPSON, JR.
